Inventor

George W. Kelley

By Watson E. Coleman
Attorney

UNITED STATES PATENT OFFICE.

GEORGE W. KELLEY, OF SPOKANE, WASHINGTON, ASSIGNOR OF ONE-HALF TO CHARLES H. HAGEMAN, OF SPOKANE, WASHINGTON.

WRENCH.

Application filed April 15, 1922. Serial No. 552,947.

To all whom it may concern:

Be it known that I, GEORGE W. KELLEY, a citizen of the United States, residing at Spokane, in the county of Spokane and 5 State of Washington, have invented certain new and useful Improvements in Wrenches, of which the following is a specification, reference being had to the accompanying drawings.

10 This invention relates to improvements in wrenches, and more particularly to improvements in wrenches of the movable jaw type.

An important object of the invention is 15 to provide a wrench having a jaw which is shiftable for coaction with either of two fixed jaws, the coaction with one jaw being such as to permit its use in engaging polygonal surfaces, as for example, the facets of a nut, and the coaction with the other jaw 20 being such as to permit its engagement with circular devices such as pipe, round iron, and the like.

A further object of the invention is to provide a device of this character wherein the 25 adjustment of the movable jaw is materially simplified and the construction of the wrench materially cheapened.

A further object of the invention is to provide a wrench having a fixed and a movable 30 jaw, one of the jaws being provided with angularly disposed jaw faces arranged in an included angle and the other of the jaws having similarly angled jaw faces arranged in an exterior angle, and a connection between the fixed and movable jaws permitting the arrangement of the movable jaw 35 so that one of its jaw faces will parallel a jaw face of the fixed jaw or so that the other of the faces of the movable jaw will 40 be arranged at an acute angle to the other of the jaw faces of the fixed jaw, the last named coacting faces of the fixed and movable jaws being provided with teeth whereby to provide an alligator wrench.

45 These and other objects I accomplish by the construction and arrangement shown in the accompanying drawings in which like reference characters designate like parts, and in which:

50 Figure 1 is a side elevation of a wrench constructed in accordance with my invention showing the movable jaw in position to form an alligator wrench;

Figure 2 is a sectional view showing the

movable jaw in position to form a nut 55 wrench;

Figure 3 is a section on the line 3—3 of Figure 2; and

Figure 4 is a perspective of the removable jaw detached.

Broadly stated, the invention consists in a fixed jaw 10 having angularly disposed jaw faces 11 and 12 and a complementary movable jaw 13 having angularly disposed jaw faces 14 and 15 which are arranged at 65 substantially the same angle as the jaw faces of the fixed jaw. The jaw faces of one of the jaws, at present disclosed as the fixed jaw 10, are arranged in an included angle and the jaw faces of the other jaw are arranged in an exterior angle, and a connection is provided between the fixed jaw 10 and the movable jaw 13 so that the movable jaw may be arranged to bring its jaw face 14 into substantial parallelism with the jaw 70 face 11 of the fixed jaw 10, or to arrange the jaw face 15 of the movable jaw at an acute angle to the jaw face 12 of the fixed jaw. The coacting jaw faces 12 and 15 are provided with teeth whereby these jaws when 75 arranged at an acute angle, as hereinbefore stated, may be employed as an alligator wrench for engaging circular surfaces such as pipe, round metal, etc.

In the present illustration the connection 80 between the head and movable jaws is provided by forming in the head a recess or slot 16 opening into the jaws 11 and 12. The walls of the slot are provided with slots 18 communicating with the slot 16 and substantially paralleling the jaw 12. The movable jaw 13 is formed with a leg 19 which is slidably mounted in the slot 16 of the fixed jaw. This leg has extending therethrough adjacent its lower end a pin 95 20, the ends of which operate within the slots 18 and one end of which is provided with a fixed head 21 abutting the outer face of one side of the head of the wrench. The opposite end is adapted for the attachment of a removable head 21^a which abuts the opposite face of the wrench head to prevent removal of the pin.

The recess 16 opens through one side face of the wrench head, as indicated at 100 22, and is provided in the wall thereof with a threaded opening 23 for the reception of a securing element whereby the spring 24

may be secured within the recess. The lower extremity of the leg 19 is provided with angularly disposed cam faces 25 and 26 for coaction with the spring. When the cam face 25 is engaged with the spring the movable jaw is held in approximately the position shown in Figure 1, with the corner portion of the jaw 14 abutting the jaw 11 of the wrench head. When in this position the toothed or serrated portions of the jaw 15 coact with the serrations of the jaw 12 to provide an alligator wrench for engagement with objects circular in cross section. When the cam face 26 is engaged with the spring the movable head has the teeth of the jaw 15 thrown into engagement with the teeth of the jaw 12 so that the movable head is held against movement after adjustment. When it is desired to regulate the distance between the faces 11 and 12, this may be accomplished by engaging the removable head with the hand and elevating the same against the action of the spring so that the teeth of the jaws 15 and 25 12 clear one another, and shifting the movable jaw.

From the foregoing it is believed to be obvious that a wrench constructed in accordance with my invention is particularly well adapted for the purpose for which it is intended by reason of the fact that the same may be readily adjusted to take different sizes of nuts or readily shifted to a position where it may be engaged with and employed for turning members circular in cross section. It will furthermore be obvious that the construction as hereinbefore set forth is capable of some change and modification without materially departing from the spirit of my invention and I accordingly do not limit myself thereto except as hereinafter claimed.

I claim:

1. A wrench embodying a head having a cutout portion forming angularly disposed jaw faces, and a shiftable and tilttable jaw likewise provided with angular jaw faces adapted to coact with adjacent jaw faces of the head for the reception of material to be held, the coaction of one pair of said faces forming an alligator wrench and the coaction of the other pair of said faces forming a wrench for engaging polygonal surfaces, the faces of the first named pair bearing gripping teeth coacting during the coaction of the last named pair of faces to hold the jaw against shifting in one direction.

2. A wrench embodying a head having a cutout portion forming angularly disposed jaw faces, a shiftable jaw provided with angular jaw faces adapted to coact with adjacent jaw faces of the head, and a connection between the head and said shiftable jaw permitting shifting of the shiftable jaw

to engage one of the jaw faces of said head or to be arranged at an angle thereto, said shiftable jaw when engaged with the jaw of said head having a jaw face substantially paralleling the other jaw face of the head, said shiftable jaw when arranged at an angle to the jaw of said head combining therewith to form an alligator wrench, said connection between the head and movable jaw maintaining the movable jaw in adjusted position.

3. A wrench comprising a head having a transverse slot therein, angularly disposed jaw faces formed in the head, one of which parallels said slot, a slot connecting the last named jaw face and the transverse slot of the head, a movable jaw having a leg extending through the last named slot and provided with an angular portion operating and rotatable in the first named slot, the last named jaw face being provided with teeth, said movable jaw being provided with angular jaw faces coacting with the jaw faces of said head to receive work to be held, the jaw of the movable head coacting with the last named jaw being provided with teeth coacting with the teeth of the last named jaw.

4. A wrench comprising a head having angularly disposed jaw faces, a recess formed in said head and opening through one of the jaw faces, said head having slots formed in the side walls thereof substantially paralleling the last named jaw and communicating with said recess, a movable jaw having a leg extending into the recess and provided with angular portions operating in the last named slots, a spring disposed within the recess, and cam faces formed upon the lower end of said leg and adapted to alternately engage said spring to maintain the movable jaw in adjusted position.

5. A wrench embodying a head having a cutout portion forming angularly disposed jaw faces, a shiftable and tilttable jaw likewise provided with angular jaw faces adapted to coact with adjacent jaw faces of the head for the reception of material to be held, the coaction of one pair of said faces forming an alligator wrench and the coaction of the other pair of said faces forming a wrench for engaging polygonal surfaces, and means for holding said movable jaw with either of the jaw faces thereof disposed to coact with its corresponding jaw face upon the head for the reception of work, the faces of the first named pair bearing gripping teeth coacting during the coaction of the last named pair of faces to hold the jaw against shifting in one direction.

6. A wrench embodying a head having a cutout portion forming angularly disposed jaw faces, a tilttable jaw likewise provided with angular jaw faces adapted to coact

with adjacent jaw faces of the head for the reception of material to be held, the coaction of one pair of said faces forming an alligator wrench and the coaction of the other pair of said faces forming a wrench for engaging polygonal surfaces, and means for holding said movable jaw with either of the jaw faces thereof disposed to coact with its corresponding jaw face upon the

head for the reception of work, said holding means yielding to permit tilting of the tilttable head to bring either of the jaw faces thereof into coaction with the corresponding jaw face of the head of the wrench. 10

In testimony whereof I hereunto affix my 15
signature.

GEORGE W. KELLEY.
